MACHINE GUN CONTROL

Victor F. Zahodiakin, Short Hills, N. J.

Application June 25, 1945, Serial No. 601,504

6 Claims. (Cl. 89—133)

1

This invention relates to the control and synchronization of machine guns. The invention is disclosed as a continuation-in-part of my copending application Serial No. 588,273, entitled Gun synchronization, filed April 14, 1945, and is directed particularly to electrical apparatus for firing the machine guns, and to a selective control system by which the guns may be fired independently of one another, even though their operation is coordinated through a common control system, in the event that one or the other should become jammed or become inoperative.

The synchronizing equipment disclosed in the aforesaid patent application comprises a primary controller for each gun, which is responsive to its operation; each gun also has a firing controller, which, when actuated, causes discharge of the gun associated with it, and each gun has a linkage interconnecting the primary controller thereof with the firing controller thereof. These linkages are cross-connected or associated with one another through a intercontroller device which provides lost motion of such nature as to prevent transmission of movement from the primary controller to the firing controller of one gun but not both. The gun first ready to be fired utilizes, or takes up, this available lost motion, and, in utilizing it renders the linkages of all guns effective for transmitting motion. Therefore, the primary controller of the gun which is last ready to be fired actuates the linkages to the firing controllers of both guns and sets off both in unison.

In the preferred embodiment of the invention for convenience in mounting and simplicity in structure, the linkage mechanism includes flexible cables interconnecting the primary controllers respectively with the intercontrol device, and interconnecting the intercontrol device with the respective firing controllers. While each gun is being loaded, that is, while a cartridge automatically is being inserted into its chamber, the cable system of that gun, or at least a part thereof, is slack. Next, when that gun is ready to be fired, the slack is taken up by the primary controller of that gun and the cable system for the gun is rendered effective for transmitting motion, but no motion actually is transmitted from the primary controller to the firing controller of that gun, because of the lost motion which is available at the intercontroller. Therefore, the firing of the gun is delayed until the other gun reaches that stage of its operation where it too is ready to be fired, whereupon the primary control of the latter gun in taking up the slack of its cable system tugs upon the entire system and actuates the

2

firing controllers of both guns to discharge them simultaneously.

As an emergency device, the intercontroller is provided with means for rendering its lost motion apparatus ineffective, and in this manner the cross-control between the guns is neutralized and each primary controller is capable of actuating its own firing control regardless of the status or condition of the other gun.

10 The present invention provides an electrical system operative in conjunction with this synchronizing apparatus for enabling the guns to be loaded safely and conveniently, to be tested for firing and to be selectively controlled. The latter feature is of considerable importance since the operation of the guns in the synchronizing system is so integrated that if one gun otherwise would fail then both would be inoperative.

Briefly, in accordance with this invention, an 20 electrical control system is provided including solenoids for governing the operability of the primary controllers, solenoids for governing the firing of the guns independently of the primary controllers, and electrically controlled means capable 25 of isolating the intercontrol unit of the synchronizing system or rendering it ineffective for coordinating the fire of the guns. The term "solenoid" as used herein is intended to include magnetic motors, electric thrusters, relays, or other 30 electrical actuating devices for exerting a mechanical movement in response to an electric impulse or electric current.

The drawings disclose a preferred embodiment of the improvement in which:

35 Figure 1 is a plan view of the synchronizing system for the guns, as disclosed in the aforesaid copending application.

Figure 2 is an electrical diagram showing the 40 interconnection of the various parts and their association with the synchronizing system.

Figure 3 is a view similar to Figure 1 showing the relative positions of the parts of the mechanism just after the guns have been fired.

Figure 4 is a view similar to Figure 3 but showing 45 the relative positions of the parts when one gun is ready to be fired before the other. In this view it will be noticed that the slack has been taken from the linkage system from the upper or left hand gun apparatus and is just about to be taken from the lower or right hand gun apparatus.

Inasmuch as the details and structure of the mechanical synchronizing system are fully disclosed and claimed in the aforesaid copending 55 application that part of the invention is referred

to only briefly here. It comprises primary controllers A and B, one for each machine gun, firing controllers C and D, one for each gun, and the intercontrol unit E. The primary controllers are governed by the gun bolts 10 which move backwardly in recoil in the direction of the dotted arrows when the guns are fired. At the forward ends of their strokes these bolt elements engage, and tip bell cranks 11, swinging the bell cranks and thereby causing their arms 12 to move the 10 rocker arms 13. The rocker arms have their far ends bearing upon arms 14 with which are associated latch arms 15. The latches 15 hold plungers 16 in a forward position against the bias of springs 17 and, when the latches are swung out of the way of the plungers, the plungers move rearwardly, in the direction of the arrow. These plungers have transmission cables 18 at their forward ends which extend to the intercontrol unit E; therefore, when the plungers 16 are released, they tug upon the respective transmission cables associated with them.

The latches 15 and the plungers 16 are reset by rearward movement of the bolts 10, that is, movement in the direction shown by the adjacent dotted arrows. In their rearward movement the bolt elements 10 engage cam surfaces 19 provided on arms 20 whereby the bolt elements are effective for swinging the levers. Arms 20 actuate arms 21 and the arms 21, in turn, thrust resetting links 22 forwardly thereby moving the plungers 16 forwardly through levers 23 which interconnect the resetting links 22 with the plungers. The latches 15 are biased to a latching position and, as the plungers are moved forwardly, the latches dispose themselves behind the plungers. Forward movement of the plungers slackens cables 18; rearward movement tugs upon the cables.

The firing controllers C and D have members 24 movable laterally thereof to press inwardly upon gun sears 25 and thereby fire the guns. The members 24 are moved laterally through the cam configurated faces 26 thereof which engage similarly configurated surfaces 27 of plungers 28 which, by means of springs 29, are biased to a relieved position. The plungers 28 are pulled forwardly, to fire the guns, through pulling movement of cables 30.

Cables 18 and 30 of the primary and firing controllers extend respectively into connection with bell cranks 31 and 32, which are arranged in pairs at opposite sides of the intercontrol unit E. Bell cranks 32-32 are pivotally connected to upper and lower links 33 having common connection with a cross bar 34 which, in turn, is connected with corresponding arms of the bell cranks 31. The other arms of the bell cranks 31 have links 35 extending respectively into connection with the arms 36 of a floating connection member 37. This latter element is guided in a slot so that it is shiftable from a centralized position. This floating connection member 37 constitutes a lost motion device in that it may shift to either side of its slot, as shown in Figure 4, when the plunger of one primary controller has been released before the other. Thus, the movement of the released plunger is absorbed in the system because of the relative position of the fulcrum point for bar 34 on lower bell crank 21. Subsequent release of the plunger of the other primary controller, for instance, the lower one shown in Figure 4, will initially cause the floating connection 37 to move back to its centralized position and then a tugging movement will be exerted upon the cables leading to the firing controllers

5 of both of the guns. As described in a later part of the specification, the present apparatus also includes means for holding the floating connection in its centralized position so that it no longer has the ability to provide lost motion. When it is held in the centralized position, then the primary controller of each gun is capable of actuating only its associated firing controller or, in other words, each gun operates as an independent unit so that the jamming or failure of one gun to operate does not effect the operation of the other.

For purposes of illustrating the operation of the system just described, let it be presumed that both guns are loaded ready for discharge and that both guns simultaneously are discharged. The bolts thereof, under recoil move rearwardly. Now, in the absence of a synchronizing system, each gun will continue to operate and fire automatically regardless of the other so long as the triggers of the guns are held. Inasmuch as it is virtually impossible to build machine guns so nearly identical in operation that they will continue to fire in unison, it will be seen that as the guns operate they will fire at different times, first one then the other. It is this alternate discharging which imposes a vibratory action on the turret upon which both of the guns may be mounted whereby their aim becomes impaired. In the operation of the present system, however, (assuming that the plungers 16 are released), the bolts 10 are thrown rearwardly when the guns fire, and the bolts move into engagement with the cam surfaces of arms 20. The movements of these levers cause the arms 22 to be swung forwardly thereby resetting plungers 16. When this occurs, the latches 15 move in behind the rearward portions of the plungers 16 and arrest the return movement thereof. Such movements slacken cables 18, this slack being taken up by the springs 29 of the firing controllers. Now, following the recoil, as the bolts move forwardly, they engage and tip bell cranks 11. The rocker arms 13 are swung to move the latches 15 to unlatching position and the plungers 16 thereby become released. If these movements occur simultaneously in both guns, then the floating connection 37 remains unaltered in its centralized position as shown in Figure 3. However, if the bolt of one gun reaches battery position before the other, then the plunger of its primary controller will be released before the other, as illustrated in the position of the plunger of the upper or left hand primary controller in Figure 4. The releasing of this plunger tugs upon the transmission cable 18 which is associated with it. The upper bell crank 31 to which this cable is connected is moved, but, since the cables 20 to the firing controllers are under the tension provided by springs 29 of the firing controllers, the swinging of the bell crank merely causes the floating connection 37 to shift from centralized position. Therefore, the motion provided by the release of the one plunger 15 is absorbed by the floating connection and is not imparted to the firing control cables of either of the guns. Thus, neither of the guns fires but one is conditioned to fire.

Meanwhile, the bolt of the other gun approaches and tips its bell crank 11 thereby releasing the plunger of the second primary controller. This plunger therefore tugs upon its transmission cable 18 and such motion is imparted to the lower bell crank 31. This causes the associated link 35 to pull upon the arm 36 of the floating connection which is now in offset

position as just described. Such a pull first causes the floating connection to be moved to its centralized position denoting complete take up of the slack, and the cable system is tensed, whereupon the remainder of the movement or pull of the plunger 16 causes both of the arms 35 to swing the bell cranks 31 outwardly, consequently the link 31 is pulled to the left as shown in Figure 3 to cause both bell cranks 32 to tug upon both firing control cables 30 in unison and thereby discharge the guns at exactly the same moment.

The firing of the guns actuates the bolts and the same cycle is repeated. From this description it will be seen that each gun is capable of causing the firing of both but neither can be fired until the other is ready to be fired.

In accordance with the present invention the resetting links 22 have L-shaped slots therein which are traversed by connecting pins 39. When the resetting links are in the position shown in Figure 1 the pins 39 are effectively connected therewith. However, in the event that the resetting links are swung into positions in which the pins 39 are aligned with the other (e. g. horizontal) portions of the slots, (Figure 3) these portions of the slots constitute clearance areas within which the pins 39 are movable without causing movement of the resetting links.

For the purpose of controlling the positions of the resetting links in effective and ineffective positions solenoids 40 are employed. These are mounted directly upon the firing controllers and comprise plungers 41 which are associated with the resetting links through link members 42.

As illustrated in Figure 2, the guns are provided with respective trigger levers which are pivotally mounted thereon as at 44. One end of each of these trigger levers is connected with a plunger 45 of a solenoid 46, there being one solenoid 46 for each gun. The trigger levers are associated in suitable manner with the guns such that when they are operated the guns are fired, for instance, through pressure of the ends thereof opposite solenoids 46 upon gun sear or trigger elements.

Each of the solenoids 46 has one terminal thereof grounded as at 47, while the opposite terminal is connected through lead 48 to one terminal of a switch 49. The opposite terminal of this switch is connected to a post 50 on a battery 51, having its other grounded, at 52.

For energizing primary controller solenoids 40 they each have one terminal grounded as at 53 while the opposite terminals thereof are connected through leads 54 to a switch 55. This switch, in turn, is connected to post 50 of the battery.

In the event that one of the guns becomes jammed, the bolt of that gun will not be operated. Such a condition may occur when the plunger of that gun is in the resetting or latched position. In such an event, the bolt of the other gun may trip its bell crank 11 to release its plunger 16 but the accompanying movement of associated transmission cable 18 will be manifest only as a lost motion movement of the floating connection 37, that is, the floating connection will be merely moved from centralized position and, since the other gun is unable to operate to restore the floating connection to its centralized or motion transmitting position, neither gun will operate and the system will be idle. However, to avoid such a circumstance, the present invention provides apparatus for bringing the floating connection back to centralized position and holding it there. This is as follows:

Intercontrol unit E has its floating connection 37 bored as at 56 and a solenoid 57 has a plunger 58 which is positioned on the intercontrol unit for insertion into the bore 56 of the floating connection. Thus, upon energization of the solenoid the plunger 58, having a suitable lead point thereon, is thrust into the bore and holds the floating connection 37 in its centralized position. This restraint of the floating connection enables the primary controller of the gun which is still capable of operating to actuate its own firing controller by transmission of the movement of its cable 18 through the now restrained connection 37 which acts merely as a fixed pivot point in the system. For instance, referring to Figure 1, assume that the plunger of the lower primary controller is released. Cable 18 will pull lower bell crank 31 shifting arm 35 thereby swinging arms 36 of the floating connection 37. This movement will swing the upper arm 35 and provide corresponding swinging movement of the upper bell crank 31 whereby the bar 34 is pulled to swing both bell cranks 32 and pull the cables 30 leading to both firing controllers. Since the upper gun is assumed to be out of operation, it will not fire but the pull upon the cable leading to the lower firing controller will cause the lower gun to discharge.

One terminal of the solenoid 57 is grounded as at 59; the other is taken to a switch 60 which is in connection with the battery post 50, through a lead 61.

Preparatory to the loading of the guns the pins 39 are aligned with the "horizontal" or clearance portions of the slots in levers 22; the latches 15 are in open position, the plungers 16 are in uncocked positions and the sear actuators 24 are in a somewhat canted position, the cam surfaces thereof being thrown toward the outermost points of the cam surfaces 27.

To load the guns all of the switches are left open. The bolts 10 are moved rearwardly, then forwardly, to insert cartridges into the gun chambers. This movement does not affect the positions of the plungers 16 because of alignment of pins 39 with the clearance portions of the slots in the links 22.

To fire the guns solenoids 40 are energized by closing switch 55. Solenoid 40 is of the "pull" type, and when energized (as is shown in Figure 1) it effectively connects pins 39 with their links 22. This operation conditions both guns for firing.

The initial shots from the guns are provided through momentary closure of switch 49 which actuates solenoids 46 thereby moving bar triggers 43 to fire the guns. After the first shots the guns are operated automatically.

To discontinue firing switch 55 is opened and solenoids 40, becoming deenergized, allow the resetting levers to move into positions in which pins 39 ride in the clearance portions of the L-shaped slots therein, thereby rendering the levers 19 ineffective for resetting plungers 16.

As previously described, should one of the guns fail to operate through insertion of an imperfect cartridge, through jamming or through damage to the gun, then its cable system is incapable of providing the necessary tension of the mechanical linkages in the intercontrol for operation of the other gun, that is, the live gun moves the floating connection 37 from its centralized position and the dead gun is not capable of restoring it. However, in accordance with the present improvement, should such a condition occur, the

operator closes switch 68 thereby causing the plunger 58 to be thrust into the bore of the floating connection 37. The bore, though disaligned, is accessible to the plunger by virtue of its pointed end and the thrusting movement therefore shifts the floating connection back to its centralized position. When this is done the linkage system of the dead gun is isolated from the linkage system of the gun still able to operate and movement of cable 43 is transferred to cable 39 independently of the bell cranks 31 and 32 of the dead gun system.

Having described my invention, I claim:

1. Mechanism for synchronizing the discharge of a pair of machine guns having gun bolts and sears comprising; cables for actuating the respective gun sears, means controlled by the bolts of the guns for tugging on the cables to actuate the sears, a floating connection between the cables for absorbing the tug exerted upon the cable of one gun when it is conditioned to fire, but not both, whereby the tug exerted upon the other cable by the other gun causes both cables to be tugged simultaneously through the floating connection to fire the guns simultaneously, means for restraining the said floating connection from floating movement, a source of current, and electro responsive means in connection with said source of current for selectively actuating said means for restraining said floating connection.

2. Means for synchronizing the discharge of multiple machine guns having sears, said mechanism comprising primary controllers, one for each gun, each primary controller having a connector extending therefrom, each primary controller comprising means for biasing said connector in one direction and latching means for holding said connector against said biasing means, firing controllers, one for each gun, for actuating the sears thereof, a linkage system including a floating member which is common to the connectors from the primary controllers and which is also in connection with the firing controllers, the said floating member being subject to limited lost motion movement responsive to the firing of one gun before another, thereby rendering the linkage system ineffective for transmitting control movements from that primary controller to its firing controller until the other gun is ready to be fired, the amount of said lost motion movement being so limited so that the linkage system is thereafter rendered effective for transmitting control movements from the primary controller of the gun last ready to be fired, and electrically controlled means for restraining said floating connection from floating movement.

3. A synchronizing system for machine guns, each having a bolt and a sear, said system including a primary controller having a translating member biased in one direction, a latch for normally holding the translating member in its biased position, means responsive to the bolt of the gun for tripping said latch and permitting said translating member to move under the influence of said biasing means, a member responsive to the movement of the gun bolt at another position thereof for relatching said translating member, electro responsive means for rendering said latch incapable of holding the translating member in its biased position, a mechanical linkage actuated by said translating member, a firing controller including a member positioned for engagement with the gun sear and actuated

to fire the gun in response to movement of said mechanical linkage and an intercontrol device in connection with said mechanical linkage including a floating connection for limiting the amount of motion capable of being transmitted through said mechanical linkage in response to coordinate control of another primary controller of another machine gun.

4. An armament system comprising; a pair of machine guns each having a primary controller thereon, an intercontrol unit, and firing controllers, one for each gun, mechanical linkages extending from the respective primary controllers to the intercontrol unit and from the intercontrol unit to the respective firing controllers, the primary controllers being effective for actuating the intercontrol unit through the mechanical linkages in response to gun operation, and the intercontroller being effective to actuate the firing controllers through the mechanical linkages and thereby discharge the guns in response to actuation of the intercontroller, said intercontroller having a lost motion device therein which is common to the mechanical linkages for limiting the transmission of motion from one primary controller to the firing controller of the same gun until the primary controller of the other gun is actuated, said intercontroller having electro responsive means associated therewith for restraining the said lost motion device against lost motion movement and a circuit including a manually operable switch for controlling said electro responsive means.

5. An armament system comprising; a pair of machine guns each having a primary controller thereon, an intercontrol unit, and firing controllers, one for each gun, motion transmitting linkages extending from the respective primary controllers to the intercontrol unit and from the intercontrol unit to the respective firing controllers, the primary controllers being effective for motivating the intercontrol unit through said linkages in response to gun operation, and the intercontrol unit being effective to actuate the firing controllers through said linkages and thereby discharge the guns in response to motivation of the intercontrol unit, the said intercontrol unit having a lost motion device therein which is common to the linkages for limiting the transmission of motion from one primary controller to the firing controller of the same gun through said linkages until the primary controller of the other gun is actuated, said intercontroller having a solenoid, means operated by said solenoid for restraining the lost motion device of the intercontrol unit against lost motion movement, whereby the primary controller of either gun is effective for actuating the firing controller thereof, and an electric circuit including a switch for energizing the said solenoid.

6. Mechanism for effecting the firing of two guns simultaneously, comprising; a primary controller for each gun which is responsive to the operation of that gun, a firing controller for each gun adapted to be actuated to cause the firing of that gun, a linkage interconnecting the primary controller of each gun with the fire controlling thereof, an intercontrol device connected in common to said linkages whereby movement of one linkage may be transmitted to the other, the said intercontrol device having a lost motion element which is effective for limiting the amount of movement capable of being transmitted through said linkages from the primary controllers to the firing controllers, the amount of lost motion being

such that it is taken up in response to the actuation of a primary controller of one gun and the linkages are thereby rendered effective for transmitting motion from the primary controller of the other gun to the firing controllers of both guns; and electro responsive means for restraining the lost motion element against lost motion movement whereby the primary controller of each gun is capable of actuating the firing controller of that gun through the intercontroller device regardless of the operation of the other gun.
